UNITED STATES PATENT OFFICE

138,287

DESIGN FOR A SMOKING PIPE BLASTER

Robert D. Jones, Charleston, W. Va.

Application October 15, 1943, Serial No. 111,369

Term of patent 14 years

(Cl. D85—7)

To all whom it may concern:

Be it known that I, Robert D. Jones, a citizen of the United States of America, residing at Charleston, county of Kanawah, and State of West Virginia, have invented a new, original, and ornamental Design for a Smoking Pipe Blaster, of which the following is a specification, reference being had to the accompanying drawing, forming a part thereof wherein:

I claim:

The ornamental design for a smoking pipe blaster, as shown.

ROBERT D. JONES.
